Chambers Brothers Company, a corporation of
Pennsylvania

Application March 27, 1935, Serial No. 13,261

5 Claims. (Cl. 91—33)

The invention relates to improved method and means for applying a coating of varnish, lacquer or the like to sheets. Such sheets are usually in color, either printed or lithographed.

5 Machines for sizing and varnishing paper sheets have long been in use.

The application of lacquer to sheets of paper involves a different problem, because varnish, when applied to a sheet by a roller, flows out smoothly before setting, while lacquer when applied with a running roller is left with ripples or ridges which do not ordinarily smooth out before the lacquer sets. These ripples or ridges run in the same direction in which the sheet travels, which give the coat of lacquer an appearance as though applied with a coarse comb. These ridges are very pronounced on the coating roller, when it is attempted to apply the lacquer with the ordinary varnishing machine.

20 The object of the present invention is to provide method and means to overcome these difficulties in the application of lacquer, whereby the lacquer may be laid smoothly upon the sheet.

The invention includes the relative and adjustable drive of the coating roller, the control of the doctor roller and the application, support, pressure regulation, and drive of a ripple roller.

25 My invention may be embodied in a new machine, or it may be applied to a standard varnishing machine.

30 By way of example I have shown different methods and means for effecting the desired object, some of which may be used in combination and some as alternatives.

35 Referring to the drawings, which illustrate merely by way of example, suitable embodiments of the invention:

Fig. 1 is a side elevation of a machine embodying my invention, with some details omitted.

40 Fig. 2 is a front elevation of the same.

Fig. 3 is a section on line 3—3 of Fig. 2.

Fig. 4 is a diagrammatic section on the line 4—4 of Fig. 2.

45 Fig. 5 is an end elevation of the fountain shown in Fig. 4, the brake drum being shown in section.

Fig. 6 is a plan view showing a different method of driving the coating roller and also of driving the doctor roller.

50 Fig. 7 is a fragmentary elevation from line 7—7 of Fig. 6.

Fig. 8 is a fragmentary elevation from line 8—8 of Fig. 6.

Fig. 9 is a fragmentary elevation showing the means for supporting and actuating the ripple roller.

Fig. 10 is a section on line 10—10 of Fig. 9.

Figs. 3 to 10 inclusive, are on larger scales than the scale of Figs. 1 and 2.

Similar numerals refer to similar parts throughout the several views.

Referring to Figs. 1 and 2, the frame 15 is provided with the usual inclined feed board or table 16, and the conveyor tapes 17, indicated in broken line, for delivering sheets to and conveying sheets from the cylinder or drum 18.

The paper is feathered on the feed board or table 16, as it would be on a sheet fed printing press. Each sheet is fed to guides and is taken by grippers on the cylinder 18 and carried around it and delivered onto the tapes 17, that usually 15 carry it into and through a dryer.

The coating is applied by the rubber covered roller 19, the doctor roller 20 regulating the thickness of the coat. When there is no sheet fed the fountain 21 must be tripped so that the roller 20 19 will not apply coating to the cylinder. The surface of the cylinder is "packed" to raise the surface represented by the size of the sheet, so that the sheet only may be coated and not the cylinder. This packing is of uniform thickness 25 and slightly less in dimensions than the sheet. This packing has a smooth oil-cloth drawn tightly over it. If this surface should become coated by accident, it can readily be cleaned off by a suitable solvent.

In the standard type of varnishing machine, the coating roller 19 runs at the same surface speed as that of the paper on the cylinder. The doctor roller 20 runs at approximately half this speed. The doctor roller may or may not run in 35 the varnish or lacquer, depending on the quantity in the fountain.

The guides, grippers and means for holding the packing and the oil-cloth cover, and the means for supporting and operating the tapes are all 40 well known and are not shown in the drawings.

In accordance with the arrangement shown in Figs. 1 to 5 inclusive, coating roller 19 is driven through a Reeves variable speed drive 23. By means of this drive it is possible to run the coating roller 19 at one-half the speed of the paper, and at any speed above that, up to the speed of the paper. In practice it has been found that excellent results are secured by running the roller 19 at approximately 72% of the speed of 50 the paper on the cylinder 18.

This percentage may be varied or adjusted to meet existing or varying conditions, due to the temperature, and consistency of the lacquer.

In accordance with the arrangement shown in 55

Figs. 1 to 5 inclusive, the driving pulley 30 is mounted on the shaft 31, which carries a pinion which drives, through an idler not shown, the gear 32 mounted on shaft 40 of the cylinder 18. The shaft 31 also carries a sprocket wheel 33 which drives through a chain 34, the sprocket 35 on the shaft 36 of the Reeves variable speed drive. The variable speed drive of the present example is of the vertical type. The shaft 37 of this drive carries the pinion 38, which drives the gear wheel 39 on the shaft 41 of the coating roller 19.

A ratchet wheel 42 is mounted on the shaft 43 of the doctor roller 20, and is actuated by a pawl 44, operated by the lever 45 mounted on the pivot or stud 46. This lever has, at its outer end, a cam roller 47 adapted to coact with a cam 48 mounted on the shaft 40. This lever 45 is also provided with an arm 49 connected at its outer end to a spring rod 50 provided with a spring 51 for normally maintaining the roller and cam in contact.

The lever 52 is mounted at 53 and provided at its upper free end with the cam roller 54, and is controlled by the spring 55 to maintain the roller in contact with the cam 48. This lever 52 is operated synchronously with the drive of the cylinder in connection with gripping the sheets.

The frame 15, upon which the above mechanism is mounted, is also provided with a shaft 56 upon which are mounted the arms 58 (see Fig. 4) which carry the fountain 21. These arms are provided with the downwardly projecting arms 59 having adjustable shoes 60 for engaging the cams 61 on the shaft of pedals 22.

By the mechanism described it will be seen that the pulley 30, which is driven from any suitable source of power, drives directly through suitable gears the cylinder 18. This pulley 30, 40 also drives through the chain and sprocket mechanism, the Reeves variable speed drive. The Reeves drive, by means of gears 38 and 39, drives the coating roller 19, while the doctor roller is actuated, upon each revolution of the cylinder, by the cam actuated pawl and ratchet mechanism. The doctor roller is normally held against rotation, between the intermittent pawl and ratchet actuations, by the brake mechanisms 24 and 26.

By a proper regulation of these mechanisms it will be seen that the relative surface speeds of the cylinder and the coating roller are secured.

The application of the coating to the paper on the cylinder may be distinctly improved by driving the coating roller at a surface speed less than the surface speed of the cylinder.

Since, by retarding the speed of the coating roller a wiping effect is produced, and this effect may be varied as required.

On the other hand, without changing the normal relation of cylinder and coating roller speeds, another valuable control may be secured by holding the doctor roller from rotation during the application of the coating to each sheet, and also by varying the pressure, by means to be described, between the doctor roller and the coating roller. It is also possible to combine these two features in securing desired results.

The machine above described contemplates an entirely new construction, as compared with the old varnishing machine, as additional room has to be provided for the cam, gears and the Reeves drive.

The following description comprises the application of the invention to the well known stand-

ard varnishing machine, with slight modifications.

In Figs. 6, 7 and 8, is shown a device adapted to accomplish the same results with less expensive mechanism, and also with a few new parts which can be placed upon existing varnishing or coating machines.

In the arrangement shown in these figures, the gear 65 is driven by the cylinder gear 32. Gear 65 runs freely on the shaft 41 of the coating roller 19, and drives the gear 66. Gear 67 is secured to the hub of gear 66 and both run freely on the shaft 43 of doctor roller 20. Gear 67 drives gear 68, which is secured to shaft 41 of the coating roller 19. 15

The ratio of these gears is such that the surface speed of the coating roller is, for example, 72% of the speed of the paper on the cylinder. Gears 67 and 68 are "change gears" so that the ratio can be readily changed, the range of 20 change being in eleven sets from equal speed to 57% of the speed of the cylinder. The equal speeds could be used when the machine is used for varnish. In this way the same machine is capable and adaptable for use for either varnish 25 or lacquer.

Gears 69 and 70 drive the doctor roller at a relatively slow speed with respect to the coating roller, thus giving the desired wiping effect and constantly presenting a fresh surface to the coating roller. This takes the place of the intermittent motion as described in the former method. 30

Means are also preferably provided for adjusting the pressure of the doctor roller against the coating roller, for example, referring to Figs. 6, 7 35 and 8, the bearings 71 of the doctor roller 20 are slidably mounted on the fountain 21, which permits of horizontal movement of roller 20, in direction toward and away from roller 19. This horizontal movement is controlled by the screw rods 40 72 threaded at one end into projections from bearings 71, while at the other end they are provided with the thrust bearing 73 secured to the front of the fountain. These rods are provided with the hand-operating handles or knobs 74, 45 whereby the attendant may conveniently adjust the pressure between these rollers at will.

As another means for securing a satisfactory application of coating to the sheets, I have provided a ripple roller 75 shown in Figs. 4, 9 and 10. It 50 will be understood that this feature may be applied either to the mechanism illustrated in Figs. 1, 2 and 3, or to the mechanism illustrated in Figs. 7, 8 and 9, or it may be utilized with advantage in connection with any sheet coating machine in which it is desired to improve the smoothness of the coat upon the sheet. 55

In accordance with this invention it has been found advantageous to provide a ripple roller positioned so as to contact with the sheet upon the cylinder a slight distance above the coating roller, and to cause the rotation of the ripple roller at a ratio approximately ten per cent of the surface speed of the sheet. It has been found desirable also to vary as required the pressure of the ripple roller against the sheet. For this purpose the ripple roller 75 is mounted in the bearings 76 at each end thereof. (See Fig. 9.) These bearings 76 are slidably mounted on brackets 77 70 secured to the fountain, so that the same may be moved in direction toward and away from the cylinder. Threaded rods 78 are slidably mounted in the extension 79 of bracket 77. The inner end of each rod is secured to a bearing block 76. A 75

spring 80 is provided between extension 79 and nut 81 on said threaded rod 78, so that the nut may be adjusted to secure the required tension of the spring between said nut and bracket for causing the required pressure of the ripple roller on the sheet upon the cylinder. The lock nuts 82 are provided at the outer end of threaded rod 78 on the opposite side of extension 79 to limit the inward movement of the ripple roller. As this 10 ripple roller is supported on the fountain 21 it follows that when the fountain is tripped to move the coating roller out of contact with the cylinder, the ripple roller is also moved out of contact with said cylinder.

15 A gear wheel 83 is mounted on the shaft 34 of the ripple roller, which gear wheel meshes with idler 85, which in turn, is driven by the pinion 86 of the shaft 44 of the coating roller, and therefore rotates synchronously at desired ratio to the 20 surface speed of the cylinder. This ratio is secured or changed as desired by providing gears 83-86 of required ratio.

What I claim is:—

1. In a device of the character described, the 25 combination of a sheet carrying cylinder, a coating roller, a doctor roller and a ripple roller, means for rotating said rollers, including means operating between the coating roller and the ripple roller for communicating a continuous drive from 30 the coating roller to the ripple roller at desired ratio, and spring controlled, adjustable bearings for varying the resilient pressure of the ripple roller upon the sheet.

2. In a device of the character described, the 35 combination with suitable supporting shafts of a sheet carrying cylinder having a gear wheel rotating therewith, a coating roller having a gear rotating therewith, a pair of loosely mounted gears in fixed rotatable relationship, one meshing with the coating roller gear, and a loosely mounted gear meshing with the other of said pair of gears and with the cylinder gear, said gears being in required ratio.

3. In a device of the character described, the combination of a sheet carrying cylinder, a coating roller and a doctor roller, and their rotatable supporting shafts, a pair of gears in fixed rotatable relationship, loosely mounted on the doctor 5 roller shaft, a pair of gears, one fixed and the other loosely mounted on the coating roller shaft, the gears of one shaft cooperating with the gears of the other shaft, and a gear on the cylinder shaft cooperating with the loose gear on the 10 coating roller shaft, said gears proportioned to secure the required differential as to the cylinder and coating roller rotations.

4. In a device of the character described, the combination with suitable supporting shafts of 15 a sheet carrying cylinder having a gear rotating therewith, a coating roller having a gear rotating therewith, a pair of loosely mounted gears in fixed rotatable relationship, one meshing with the coating roller gear, and a loosely mounted gear 20 meshing with the other of said pair of gears and with the cylinder gear, the gear fixed to the coating roller shaft and one of the pair of loosely mounted gears being removable for exchange with other gears for changing the ratio between 25 surface speeds of the coating roller and of the sheet upon the cylinder.

5. In a device of the character described, the combination with suitable supporting shafts of 30 a sheet carrying cylinder having a gear rotating therewith, a coating roller having a gear rotating therewith, a pair of loosely mounted gears in fixed rotatable relationship, one meshing with the coating roller gear, a loosely mounted gear 35 meshing with the other of said pair of gears and with the cylinder gear, a doctor roller having a gear rotating therewith, and a gear rotating with the coating roller of required ratio and cooperating with the gear of the doctor roller.

HOWARD K. KING. 40
